UNITED STATES PATENT OFFICE.

CALVIN DEAN, OF PROVIDENCE, RHODE ISLAND.

DESIGN FOR AN EMBLEM, BUTTON, RING-TOP, PIN, OR ARTICLE OF SIMILAR NATURE.

53,705.

Specification for Design.

Patented Aug. 19, 1919.

Application filed January 25, 1919. Serial No. 273,164. Term of patent 3½ years.

To all whom it may concern:

Be it known that I, CALVIN DEAN, citizen of the United States, residing at Providence, in the county of Providence and State of Rhode Island, have invented a certain new, original, and ornamental Design for an Emblem, Button, Ring-Top, Pin, or Article of Similar Nature, of which the following is a specification.

In the drawing, which forms a part of this

specification, the figure is a face view of an emblem illustrating my new design.

I claim:—

The ornamental design for an emblem, button, ring top, pin, or article of similar nature, as shown.

In testimony whereof I have affixed my signature.

CALVIN DEAN.
